UNITED STATES PATENT OFFICE.

JOHN L. MONTGOMERY, OF STONEHAM, MASSACHUSETTS.

SHADE CONSTRUCTION FOR PIVOTED WINDOWS.

Application filed April 27, 1921. Serial No. 464,782.

To all whom it may concern:

Be it known that I, JOHN L. MONTGOMERY, a citizen of the United States, residing in Stoneham, in the county of Middlesex and 5 State of Massachusetts, have invented an Improvement in Shade Construction for Pivoted Windows, of which the following description, in connection with the accompanying drawings, is a specification, like 10 characters on the drawings representing like parts.

This invention relates to a shade or curtain construction especially designed and adapted for use with pivoted windows, such, 15 for instance, as the horizontally pivoted sash sections in the windows of mills and like buildings, whose outer walls are largely composed of glass.

The invention has for its object to provide 20 the pivoted windows or pivoted sections of large windows in the side walls of a building with shades or curtains, which are capable of being lowered with the pivoted window in its open position without interference 25 with the open window.

The invention further has for its object to provide a shade or curtain construction, in which the free end of the shade or curtain is in sliding engagement with guide 30 rods which are movable and are operatively connected with the movable window to be moved thereby, and which permit the shade to be lowered with a minimum tension and without disturbing the position of the 35 window.

These and other features of the invention will be pointed out in the claims at the end of this specification.

Fig. 1 is an elevation of one form of window provided with a shade or curtain construction embodying this invention.

Fig. 2, a vertical section on the line 2—2, Fig. 1, with the shade carried by the pivoted window omitted to show one of the shade fixtures and the guide rod co-operating therewith.

Fig. 3, a horizontal section on the line 3—3, Fig. 2, through the shade fixture.

Fig. 4, a detail in plan to be referred to.

Fig. 5, a vertical section on the line 2—2,

Fig. 1, with the pivoted window in an open position, and

Fig. 6, an enlarged detail of the shade fixture shown in Fig. 5.

Referring to the drawing, *a* represents a 55 window provided with horizontal side pivots *b* mounted to turn in a casing *c*, which in the present instance forms part of a stationary window comprising side lights 10, top lights 12 and bottom lights 13. 60

The stationary window may form part of the upright wall of a mill or other structure such as now commonly constructed.

The window *a* has co-operating with it a shade or curtain 14 of known or usual construction, and said shade is connected with said window to move therewith when the latter is turned on its pivots *b* to open and close the same.

In the present instance, the shade 14 is 70 made wide enough to cover a portion of the side lights 10, and is mounted at its ends in fixtures, which may be of any suitable or desired construction, except that in the present instance said fixtures are pivoted at 75 16 to supports, herein shown as arms 17 extended from brackets or bars 18, which are screwed or otherwise attached to the top cross bar of the sash 19 of the pivoted window *a*. Each shade fixture may be made 80 as herein shown and comprises two plates or members 20, 21, secured together by studs 22, and one of the plates as 21 is pivoted to the arm 17, and the other is provided with ears 23 through which is extended a guide 85 rod 24, screw-threaded at its lower end to engage nuts 25 located on opposite sides of an arm 26, through which the guide rod 24 is extended. The arm 26 is attached to a bracket or bar 27 pivoted at 28 to the arm 29 of a bracket 30 attached to the casing 31 of the stationary window, or to a stationary part of the window frame.

The guide rods 24 are free at their upper ends to slide through the ears 23 of the curtain fixtures. The guide rods 24 also extend through suitable guides 32 attached to the free end of the shade 14, preferably to the usual shade stick or slat (not shown).

When the window *a* is closed, the guide 100

rods 24 are substantially parallel with the wall of the building, which is represented by the stationary window, and the shade can be lowered or drawn down in the usual manner by a suitable cord, not shown, and may be held in its lowered position by fastening the cord to a button or other device 34 attached to the stationary window casing.

10 When it is desired to ventilate the building, the window *a* is turned on its pivots *b*, usually so that the top half of the window *a* projects into the room or building, and the shade 14 is moved with the window away from the wall of the building more or less according to the amount the window is opened. As the shade is moved into the room, the free ends of the guide rods 24 are carried by the shade fixtures away from the wall of the building, which is permitted by the guide rods turning at their lower ends on their pivots 28.

25 As the upper or free ends of the guide rods are moved away from the wall of the building, the shade fixtures are turned on their pivots 16 by the guide rods and the ears 23 slide down on the same after the manner represented in Fig. 5. It will thus be seen, that the shade is carried by the 30 movable window and that the latter can be opened to any extent desired without interfering with the shade, which is free to be raised and lowered on its guide rods with a minimum tension or pull in all positions of the window.

35 By reference to Fig. 1, it will also be observed that the shade 14 co-operates with the stationary side lights 10 as well as with the movable window *a*, which is effected by 40 making the supporting brackets 18 long enough to have the shade cover the side lights 10 and yet be movable with the window *a*.

45 If the shade is to be used with the window *a* alone, as in those constructions wherein the side lights 10 are omitted, the brackets 18 will be made shorter than those herein shown and used with a narrower shade of substantially the same width as the window *a*.

50 When the building is provided with top lights 12 as herein shown, a supplemental shade 40 of usual construction will be used to cover the same.

55 By reference to Fig. 2, it will be seen that when the window *a* is closed, the guide rods 24 are in a vertical position and that the shade when drawn down has its free end guided by said rods, and that when the 60 window *a* is opened, the free ends of the guide rods are moved away from the wall of the building and the free end of the shade remains in sliding engagement with the guide rods and slides thereon when the

curtain is raised or lowered. It will also be noticed that when the window is open, an extreme position of which is shown in Fig. 5, and the shade is drawn or lowered, the free end thereof is restrained from movement under the influence of the air by the guide rods. As a result, the shade can be drawn down with a minimum tension or pull, as the pull or tension required is only such as is required to overcome the tension of the spring of the shade, and is not such as will move the window from its adjusted open position.

Claims:

1. The combination with a window provided with stationary side lights and with a pivoted section between said side lights, of brackets attached to said pivoted section and extended beyond the sides of the same, a shade of greater width than said pivoted section to cover the latter and said side lights, fixtures pivoted to said brackets to support said shade, and guide rods for the free end of said shade pivoted at one end and having their opposite ends in sliding engagement with said pivoted fixtures.

2. The combination with a pivoted window sash, of a shade therefor carried thereby to move therewith, pivoted fixtures for said shade movable with said window sash, and guide rods for the free end of the shade in sliding engagement with said pivoted fixtures and pivotally secured to a support stationary with relation to said sash.

3. The combination with a window pivoted at its sides between its ends, of a shade therefor carried thereby to move therewith, and pivoted fixtures for said shade movable with said window, and means co-operating with said fixtures to effect pivotal movement thereof when said window is opened or closed and to guide the free end of the shade in its movement to cover and uncover the window.

4. The combination with a window pivoted at its sides between its ends, of a shade therefor, movable fixtures for said shade carried by said window, and movable guide rods co-operating with said movable fixtures and with which said shade is engaged to slide thereon in the different positions of the window.

5. The combination with a pivoted window sash, of a shade therefor movable therewith, pivoted guide rods with which the free end of the shade is engaged to slide thereon, a support stationary with relation to the pivoted window and to which said guide rods are pivoted, and means movable with said window and co-operating with said guide rods to effect movement of the latter on their pivots by said window.

6. The combination with a movable window sash, of a shade therefor movable

therewith, guide rods movable with relation to said window sash and with which the free end of the shade is engaged to slide thereon, and means for connecting said 5 guide rods with said window sash to effect movement of the guide rods by said window sash.

7. The combination with a pivoted window sash, of a shade therefor movable

therewith, and guide rods pivoted to a support stationary with relation to said window sash and with which the free end of the shade engages to slide thereon in the different adjusted positions of said window.

In testimony whereof, I have signed my 15 name to this specification.

JOHN L. MONTGOMERY.
